UNITED STATES PATENT OFFICE.

CARL LÄUCHLI, OF DUBENDORF, NEAR ZURICH, SWITZERLAND, ASSIGNOR TO THE FIRM CONTINENTAL-LICHT- UND APPARATEBAU-GESELLSCHAFT, OF FRANKFURT-ON-THE-MAIN, GERMANY.

GAS GENERATOR.

Application filed August 15, 1921. Serial No. 492,405.

(GRANTED UNDER THE PROVISIONS OF THE ACT OF MARCH 3, 1921, 41 STAT L., 1313.)

To all whom it may concern:

Be it known that I, CARL LÄUCHLI, a citizen of the Republic of Switzerland, residing at Dubendorf, near Zurich, Switzerland, have invented certain new and useful Improvements in Gas Generators (for which I have filed applications in Switzerland May 15, 1920, Patent No. 88153; in Switzerland August 5, 1920, Patent No. 89369; in France 5 May 14, 1921, application No. 144693; in Italy May 14, 1921, application No. 302/1837; in Belgium May 14, 1921, application No. 237074; in Sweden May 17, 1921, application 10 No. 2010/21; in Austria May 19, 1921, not yet numbered; in Denmark May 21, 1921, application No. 1346/21; in Norway June 2, 1921, application No. 24126/21; in Hungary June 2, 1921, application No. 12111; in England July 18, 1921, application No. 20 19366; in Holland, application number and date not yet known; in Germany May 6, 1921, application No. 30589); and I do hereby declare the following to be a clear, full, and exact description of the invention, 25 such as will enable others skilled in the art to which it appertains to make and use the same, reference being had to the accompanying drawings, and to letters or figures of reference marked thereon, which form a 30 part of this specification.

This invention relates to improvements in gas generators and particularly to a device for automatic pressure regulation in acetylene high pressure generators of the type in 35 which the fluctuations of the pressure in a gas container caused by changes in the consumption of gas are utilized for regulating the generation of gas by influencing the access of the water to the calcium carbide.

According to the invention the gas produced escapes below a bell which forms part 40 of a floating device arranged in the liquid of a gas container. The device alters its elevation in the liquid upon an alteration 45 of the gas pressure inside the gas container, so that the thereby caused variation of the hydrostatic pressure at the lower edge of the bell, which pressure the gas has to over-

come on flowing into the container, influences the level of the liquid in the producer proper. 50

The float may be constructed as an enclosed hollow body. Its volume and therefore its displacement varies with the variation of the gas pressure and water pressure 55 in the gas container, so that the enclosed body is expanded when said pressure decreases and rises in the liquid and said body is compressed upon an increase in said pressure and sinks down in the liquid of the container. 60

On the accompanying drawings two constructional forms of the embodiment of the invention are shown by way of example, in 65 which drawings:

Fig. 1 is a vertical section through a high pressure gas generator, with parts shown in elevation,

Fig. 2 is a vertical section through the floating device with its parts in the operative position at the beginning of the gas production, 70

Fig. 3 illustrates a detail of the gas bell on an enlarged scale.

Fig. 4 is a vertical section with parts 75 shown in elevation through a high pressure gas generator of the same type as that shown in Fig. 1 but provided with a modified construction of the regulating float,

Fig. 5 is an end view of the float partly 80 shown in section, and

Fig. 6 is a vertical section along line VI—VI of Fig. 5.

Referring to the first constructional example illustrated in Figs. 1-3, 1 denotes the 85 completely enclosed container of the generator which is filled up to a certain height with water 2. The space 3 above the water level serves as gas reservoir. Inside the container 1 another container 4 is provided which is the gas producer proper and serves for holding the carbide 5. The container 4 is closed at its upper end by means of a cover 6, the lower end is left open to give the water access to the carbide. A grate 7 90 provided inside the container 4 prevents the

carbide from falling out of the open end of the container 4; a rod 8 is connected to the grate 7 and extends inside the container 4 in an upward direction, so that upon a removal of the cover 6 a shaking of the carbide is rendered possible in order to separate the refuse, that is formed by the action of the water on the carbide, from the pieces of carbide. The lower part of the container 4 is surrounded by a closed receptacle 9 the upper end of which is connected in an airtight manner to container 4 and the lower portion of which, that projects beyond the container 1 is hermetically connected to the latter. A cock 10 is provided in the lowermost part of receptacle 9 for the purpose of drawing off the slimy refuse during the working of the gas generator. A cover 11 is provided for permitting of a thorough cleaning of the receptacle 9. The latter is connected by means of a conduit 12 with the water space 2 of the receptacle 1. A cock 13 is inserted in said conduit 12, which cock is actuated by means of a rod 14 and a hand lever 15; the latter is so arranged that in its position corresponding to the open position of the cock 13 it projects beyond the edge of the cover 6, whereby the latter can only be removed after the cock 13 has been closed. The gas generated in the receptacle 4 is led through a conduit 16 to the receptacle 1, the conduit 16 ending inside a bell 17. This gas bell 17 is designed as a floating body the lateral walls 35 of which consist of two concentrically arranged cylinders. The outer cylinder of the lowermost part 18 of the gas bell 17 is of a greater diameter than the upper part; in its top part the bell is completely closed and 40 in its lower part the annular portion between the two cylinders is closed. The inner cylinder of the gas bell is provided with a small aperture 20 near the upper end of the enlarged portion and the outer cylinder 45 is provided with a small aperture 22 near the lower end of said enlarged portion. The gas bell 17 is adapted to move freely within a cylinder 23 the inside diameter of which is slightly larger than the outside diameter 50 of the upper part of said bell. The cylinder 23 is at certain points of its circumference connected to an annular floating body 24 concentrically arranged with respect to said cylinder. The float 24 is closed at its 55 upper end and open at its lower end. The cylinder 23 is closed at its upper end, and near its closed end a hole 25 is provided through which gas which has collected between the bell 17 and the cylinder 23 can 60 escape into the gas space of the container 3. To the lower end of the cylinder 23 stops 26 are fixed that limit the downward movement of the gas bell 17; when the whole floating device is in its lowermost position 65 it is supported by said stops 26 resting on

the floor of the container 1. Another stop 27 is provided inside the container 1 against which the cylinder 23 abuts when the floating device is in its uppermost position. A conduit 28 serves to draw off the gas generated. 29 denotes a safety valve with which the producer 4 is provided.

The manner of operation of the above described gas generator is as follows:

Fig. 1 illustrates the upper position of the floating device. The gas bell 17 is also shown in its uppermost position abutting against the upper end of the cylinder 23 and it shall be assumed for the following explanation that the gas bell remains in this position. In this upper position the water level in the interior of the float 24 will adjust itself to such a height and the gas above said level inside the float 24 will be compressed to such a degree that its pressure corresponds to the gas pressure in the gas space 3 plus a hydrostatic pressure that is equal to the difference in the liquid levels of container 1 and float 24. The volume of the float 24 and the weight of the whole floating device is so dimensioned that at the above pressure the gas inside the float 24 takes up such a volume that the weight of a corresponding volume of water is greater than the weight of all the parts of the floating device. In this upper position of the latter the gas generated in the producer 4 has to overcome a back-pressure that is equal to the hydrostatic pressure at the lower edge of the gas bell 17, as, in consequence of the equalizing pipe 12 the liquid in the receptacle 9 and in the producer 4 respectively has the same pressure as in the container 1 increased by hydrostatic pressure corresponding to the water level difference in the containers 1 and 9. In order to cause the gas to flow from the producer 4 into the gas space of the container 1 the pressure inside the producer must be such that the water level in the container 9 is slightly below the lower edge of the gas bell 17. In this upper position of the floating device the greatest production of gas takes place.

If now for any reasons the consumption of gas diminishes the gas pressure in the gas reservoir 3 will be increased. This higher pressure causes a compression of the gas volume inside the float 24, its displacement becomes smaller and the whole device will sink rapidly until it rests by means of the stops 26 on the floor of the container 1. Thereby the hydrostatic pressure at the lower edge of the gas bell 17 increases rapidly and a further flow of the gases produced past the lower edge of the gas bell into the container is at once prevented. The gas generated in the producer causes a rise of pressure in the latter by which the water is forced out of said producer until its level

is below the carbide, whereupon any further production of gas ceases.

Upon more gas being consumed the pressure in the gas reservoir 3 of the container 5 drops, the gas volume inside the float 24 expands and the greater displacement causes a movement of the whole floating device into its upper position; the liquid level of the producer 4 rises to whereby gas is again generated; the pressure of the gas in the container 1 is thus automatically regulated. By adjusting the weights of the parts of the floating device the sensitiveness of this regulating device can be varied at will.

15 In working such gas generating plants the water has to be renewed from time to time. Thereby it happens that more or less air enters the interior of the float 24 for instance by diffusion. If now the apparatus 20 be set to work again the regulation, the weights of which have been adjusted for a float 24 containing gas, will no longer work with the same sensitiveness. In order to prevent this drawback the gas bell is arranged as a float and is provided with the apertures 20 and 22. The operation of the bell when filling the container 1 is as follows:

Through the opening 20 gas may escape and water enters into the interior of the bell 30 17. The latter is so dimensioned that upon this decrease of the displacement the bell still rests on the stops 26 even when the water level has attained during the filling of the container 1 such a height that the 35 generation of gas starts. The path of the gas passing the lower edges of the bell 17 is deflected by the larger diameter of the lower part of said bell in its lowest position in such a manner that it enters for the greater 40 part the float 24 (Fig. 2) and drives out the air contained therein. At the same time gas will enter into the interior of the bell 17 through the aperture 20 and will at first displace the air inside said bell and there- 45 after the water. The bell 17 will thereupon rise into its upper position and remain in this upper position during the working of the device. In this position of the bell 17 the gas produced rises in the annular space 50 between the float 24 and the bell 17.

In the second constructional example illustrated in Figs. 4-6 the float consists essentially of two circular membranes 30 and 31, the edges of which are inclined to- 55 wards each other and welded together at 32, so that a hollow disc is formed. The interior of this float may be connected to the surrounding atmosphere or to a pressure device by means of a radially arranged cock 60 33. A vertically arranged pipe 34 closed at its upper end and serving at the same time as a guide and as a gas bell passes diametri- 65 cally into the disc float up to near its circumfer- ence. The pipe 34 has a slightly larger inside diameter than the outside di-

ameter of the pipe 16 which serves to conduct the generated gas from the producer 4 to the container 1.

The above described float works as fol- 70 lows:

In Fig. 4 the float filled with compressed air of 0.2-0.3 atm. surplus pressure is illustrated in its upper position, in which it abuts against a stop 27 which limits its movement in the upward direction. In this position 75 the displacement volume of the float consisting of the two membranes will adjust itself in accordance with the pressure of the gas in the reservoir 3. The volume of the float and its weight are so dimensioned, that at a desired pressure of the gas in the container 80 the weight of the volume of water displaced by the float is greater than the weight of the latter.

With the float in the upper position shown 85 in Fig. 4 the gas generated in the producer 4 has to overcome a back pressure that is equal to the hydrostatic pressure present at the lower edge of the pipe 34 acting as gas bell, as has been described in the first con- structional example. The water level in the interior of the producer 4 adjusts itself to approximately the height of the lower edge of the pipe 34 and the maximum pro- 90 duction of gas takes place.

Upon a rise of the pressure of the gas in the container 1 owing to a smaller con- sumption of gas the membranes of the float 100 are pressed against each other, the displace- ment of the float becomes smaller, the float sinks and the generating of gas is stopped as has been described; upon a decrease in the gas pressure inside the container 1 the float rises and gas is generated again.

This float presents the advantage that the air contained in it is completely enclosed so that no loss of air occurs and the float 105 will therefore be continuously effective.

I claim:

1. An acetylene high-pressure generator, 110 comprising a closed container having a water space and a space above said water space serving as a reservoir for the gas generated, a gas producer adapted to contain carbide in its upper part and to contain water in its lower part, a gas bell ar- ranged in the water space in said container and adapted to alter its elevation in dependency upon the variations of the pressure of the gas in said reservoir, and a conduit for the gas from the producer to said container ending below said bell whereby the height of the water level in said producer depends on the hydrostatic head at the lower edge 115 of said bell.

2. An acetylene high-pressure generator, 120 comprising a closed container having a water space and a space above the water serving as a reservoir for the gas generated, a gas producer consisting of a completely 125

- closed receptacle and adapted to receive the carbide in its upper part and water in its lower part, a conduit connecting the water space of said container to the water space of 6 said producer, a gas bell in the water space in said container and adapted to alter its elevation in said liquid in dependency upon the variations of the pressure of the gas in said reservoir, and a conduit for the gas 10 from said producer to said container ending below said bell whereby the height of the water level in said producer depends on the hydrostatic head at the lower edge of said bell.
- 15 3. An acetylene high-pressure generator, comprising a closed container having a water space and a space above the water space serving as a reservoir for the gas generated, a gas producer consisting of a 20 completely closed receptacle arranged for the greater part inside said container and adapted to receive carbide in its upper part and water in its lower part, a conduit connecting the water space of said container 25 to the water space of said producer, a gas bell combined with a float and placed in the water space in said container and adapted to alter its elevation in said liquid in dependency upon the variations of the 30 pressure of the gas in said reservoir, and a conduit for the gas from said producer to said container ending below said bell whereby the height of the water level in said 35 producer depends on the hydrostatic head at the lower edge of said bell.
- 40 4. An acetylene high-pressure generator, comprising a closed container having a water space and a space above the water space serving as a reservoir for the gas generated, a gas producer consisting of a 45 completely closed receptacle arranged for the greater part inside said container and

adapted to receive the carbide in its upper part and water in its lower part, a conduit connecting the water space of said container to the water space of said producer, a gas bell rigidly fixed to a float consisting of a closed hollow body in the water space in said container and adapted to alter its elevation in the water upon the displacement 50 volume of said float being altered in dependency upon the variations of the pressure of the gas in said reservoir, and a conduit for the gas from said producer to said container ending below said bell whereby the height of the water level in said producer depends on the hydrostatic head at the lower edge of said bell.

5. An acetylene high-pressure generator, comprising a closed container having a water space and a space above said water space serving as a reservoir for the gas generated, a gas producer consisting of a completely closed receptacle arranged for the greater part inside said container and 60 adapted to receive carbide in its upper part and water in its lower part, a conduit connecting the water space of said container to the water space of said producer, a gas bell rigidly fixed to a float consisting of 65 two circular membranes connected together to form a closed hollow body in the water space in said container and adapted to alter its elevation in the water in said water space upon the displacement volume of said 70 float being altered in dependency upon the variations of the pressure of the gas in said reservoir, and a conduit for the gas from said producer to said container ending below said bell whereby the height of the water level in said producer depends on the 75 hydrostatic head at the lower edge of said bell.

CARL LÄUCHLI.
